(57) **CLAIM**

We claim the ornamental design of a coverage unit housing, as shown and described.

DESCRIPTION

The design consists of the features of shape and configuration of the coverage unit housing as shown in the attached drawings. The drawings show two designs which do not differ substantially from each other. FIGS. 1 through 4 show the first embodiment and FIGS. 5 and 6 show the second embodiment. The second embodiment shows a segment of the bracket for optional suspension mounting of the coverage unit housing.

FIG. 1 is a front perspective view of the coverage unit housing showing my new design;

FIG. 2 is a rear perspective view thereof;

FIG. 3 is a side elevation view thereof;

FIG. 4 is a front elevation view thereof;

FIG. 5 is a top elevation view thereof;

FIG. 6 is a bottom elevation view thereof; and,

FIG. 7 is a rear elevation view thereof.

The broken line showing of the environment is for illustrative purpose only and forms no part of the claimed design.
